DESIGN FOR A COMBINED LAMP STAND AND SHADE

Daniel G. Spotts, Batavia, Ill.

Application July 30, 1941, Serial No. 102,564

Term of patent 3½ years

To all whom it may concern:

Be it known that I, Daniel G. Spotts, a citizen of the United States, residing at Batavia, in the county of Kane and State of Illinois, have invented a new, original, and ornamental Design for a Combined Lamp Stand and Shade, of which the following is a specification, reference being had to the accompanying drawing forming part thereof.

In the drawing, the figure is a side elevation of the combined lamp stand and shade, embodying my new design.

The combined lamp stand and shade is approximately symmetrical about its vertical axis, and the surface ornamentation applied to the shade continues therearound.

I claim:

The ornamental design for a combined lamp stand and shade, substantially as shown and described.

DANIEL G. SPOTTS.
